ROLLER GUIDE FOR PLOW BLADE

Michael Hertz, 520 Dorseyville Road, Pittsburgh 38, Pa.

Filed Jan. 19, 1960, Ser. No. 3,392

4 Claims. (Cl. 37—46)

This invention is directed to a roller guide for a plow blade, particularly for use on a snow plow blade. The guide is mounted on either or both transverse vertical edges of the blade to protect the blade from abrasion against curbs, buildings and the like when removing snow from adjoining areas.

Guides for snow plow blades are well known; however, none of these known guides have ever attained commercial success since they lack rugged construction, ease of assembly and disassembly, freedom from jamming and freeze-ups, long-life and low maintenance costs.

My invention overcomes all of the deficiencies of the known snow plow guides. My guide is extremely durable and rigid in construction; it is simple to assemble and disassemble by use of common well-known tools; it has only a limited number of moving parts, thereby insuring low maintenance costs; and it is so constructed that any entry of ice, snow, and undesirable materials into the moving parts of the guide is hindered or prevented.

I have described a presently preferred embodiment of my invention in the following drawings, in which:

Figure 1 is a side elevation view of my roller guide mounted on a plow blade;

Figure 2 is a front elevation view of my roller guide mounted on a plow blade;

Figure 3 is an enlarged front elevation view of my roller guide with parts removed for clarity;

Figure 4 is a plan view of my roller guide;

Figure 5 is a cross-section of the top portion of my roller guide taken on line V—V of Figure 4;

Figure 6 is a cross-section on line VI—VI of Figure 3;

Figure 7 is a perspective of a modified form of a frame for my roller guide;

Figure 8 is a perspective of another modified form of frame for my roller guide; and

Figure 9 is a cross-section through the modified form of frame shown in Figure 7.

Briefly the present invention includes a roller guide having a frame with spaced support plates affixed thereto, and a vertical bearing mounted roller rotatable about an axle positioned in holes in the support plates.

More specifically, a roller guide 10 is affixed to either or both transverse vertical edges of a plow blade 11 having a replaceable lower edge 12. The plow blade 11 and its manner of affixation to a vehicle is well known.

The guide 10 is affixed to the edge of the plow blade 11 in any desired manner, such as welding or bolting an angle plate 13 to the blade 11 and also welding or bolting the angle plate 13 to the guide.

The guide includes a frame 14 having a first leg 15 affixed at right angles to a second leg 16. Preferably this frame 14 is a conventional angle structure. A top support plate 17 is welded to the inside of the frame 14 near the upper end of the frame. A bottom support plate 18 is welded to the inside of the frame 14 near the bottom of the frame.

The top support plate 17 has a hole 19 drilled through it and the bottom support 18 has a hole 20 bored partway

2

through it. The holes 19 and 20 are in vertical alignment with each other. The bottom hole 20 has a smaller hole 21 opening into it from the bottom of the support plate 18.

A circular shaft 22 is positioned in the holes 19 and 20 and spans the space between the support plates and holes. The holes 19 and 20 are sufficiently large to provide a loose fit for the shaft. A hole 23 is bored axially into the top support plate 17 and threaded to admit a set-screw 24. The hole 23 opens axially into hole 19. The set-screw 24 is tightened against a flat area on the upper end of shaft 22 to prevent rotation of the shaft in holes 19 and 20 and aid in locking the shaft within the holes 19 and 20. The lower end of shaft 22 also has a flat area against which the set-screw 24 abuts when the shaft is inverted as described hereinafter.

A tubular roller 25 has "Oilite" bearings 26 and 27 at its upper and lower ends. The shaft 22 passes through and has a sliding fit within the bearings 26 and 27 and the bearings have a press-fit within openings in the upper and lower ends of the roller 25.

Each of the bearings 26 and 27 have axially extending flanges extending beyond and overlapping the ends of the roller 25. An opening 28 through the roller is of sufficient size to freely admit the shaft 22. Thus, roller 25 rotates freely about the stationary shaft 22 on bearings 26 and 27.

A small rectangular keeper plate 29 is positioned above the top support plate 17 and covers the upper end of hole 19. This keeper plate is affixed to the top support plate 17 by a bolt 30 which threads into a hole in the top support plate 17. The keeper plate tightly covers the top of hole 19 to prevent entry of undesirable material such as snow, ice, dirt, cinders, etc., into the hole 19.

The roller 25 is only of sufficient height to permit its introduction plus the thickness of the flanges of the bearings 26 and 27 within the space between the upper and lower support plates 17 and 18. This insures that no undesirable material will enter between the support plate and the rollers.

The shaft 22 rides on the bottom face of hole 20 in the bottom support plate 18.

If any undesirable material should enter between the flange of the bearing 26 and the upper face of the bottom support plate 18, it passes downwardly through hole 20 and out hole 21 through the bottom of support plate 18. The hole 21 also provides an opening for lubrication of the surface between the bottom of shaft 22 and the bottom of hole 20.

My roller guide is frequently used against low curbs such as shown in Figure 3 and thus only the lower half of roller 25 is subjected to abrasion and wear. I have found that it is desirable to be able to invert the roller 25 so that the unworn top half of the roller can be used. To accomplish this, it is necessary to unthread the bolt 30, thereby removing the keeper plate 29, loosen set-screw 24, and push a screw-driver or similar instrument up through the hole 21, thereby pushing shaft 22 upward out of holes 19 and 20 and out of the roller 25. The roller 25 is then removed from between the support plates 17 and 18; inverted; and the shaft 22 inserted through the hole 19, through the opening in the roller 25 and into hole 20. The keeper plate is then replaced as shown in Figure 3 and set screw 24 tightened. Both the upper and lower end of shaft 22 has a flat portion against which the set-screw 24 may be threaded to prevent rotation of shaft 22.

I have also found that in using my guide in certain types of snow, particularly the type containing large amounts of unfrozen moisture, the snow is packed between the roller 25 and the frame 14. The snow is packed at the juncture of the legs 15 and 16 on the inside of the frame. It is of utmost importance that the roller be free to rotate at all times since if it locks, a flat spot

will be quickly worn on the roller due to abrasion against a curb or building. To insure that there is no locking of the roller due to packing of the snow as above stated, I have cut a plurality of holes 31 in the frame as shown in Figure 7. These holes 31 are cut at the juncture of the legs 15 and 16 to insure that the snow entering between the inside of the frame and the roller will pass out of the frame through the holes 31. I have also shown a continuous hole 32 in a modified form of frame as shown in Figure 8 to serve the same purpose as holes 31. The particular configuration or location of these holes 31 and 32 is not important; however, I have found that the best location for the holes is at the juncture of the legs 15 and 16.

My roller is mounted in a vertical position as shown in Figure 1 to insure that the roller will rotate against any curb or building which it may abut. It is undesirable to mount the roller at an angle other than vertical since it will then be dragged against any abutting curb and quickly abraded; however, it is within the scope of my invention to mount the roller at any angle.

I have also found that it is desirable to coat the outer surface of roller 25 with a rubber material to reduce the abrasion of the roller against curbs and the like.

I have also found that the preferable height for the roller 25 is 6" and the preferable diameter 2½". The shaft 22 is preferably 1" diameter.

While I have described a present preferred embodiment of my invention, it may be otherwise embodied within the scope of the following claims.

I claim:

1. A snow plow blade including a guide rigidly mounted on the blade to protect the transverse vertical edge of the blade from abrasion against rigid structures, said guide comprising an elongated vertically extending L-shaped frame having first and second legs united along a vertically extending edge; top and bottom support plates affixed rigidly to the inside of said L-shaped frame; said support plates being spaced from and substantially parallel to each other; a circular hole extending vertically through said top support plate; a circular hole extending vertically through a portion of said bottom support plate and having a bottom face directed upward toward said top support plate; said holes being in vertical alignment; a circular shaft extending vertically through said hole in the top support plate and spanning the space between the support plates into the hole in the bottom support plate; means engaged with said guide and shaft to maintain the shaft immovably in said holes; a cylindrical roller surrounding and rotatable about said shaft; said roller being

positioned between and in spaced relationship to said support plates; and a pair of bearings affixed inside said roller and having openings in alignment with said holes in the support plates such that the shaft is slidably mounted in the bearings to permit revolution of the roller with said shaft as the axis of revolution.

2. A blade according to claim 1 wherein said means to maintain the shaft immovable within the holes is a set-screw threadably engaged with the top support plate and in locking engagement with the shaft; and a keeper plate removably affixed to the upper side of the top support plate, said keeper plate being positioned over the hole in the top support plate; and a vertical opening extending from the hole in the bottom support plate to the lower face of the bottom support plate; such that the keeper plate may be removed, the set-screw unlocked from the shaft and the shaft removed from the guide by insertion of a pushing device upward through said vertical opening in the bottom support plate to push the shaft upward out of the holes and roller, thereby permitting inversion of the roller if wear on the lower part of the roller is excessive.

3. A blade according to claim 1 wherein said bearings have flat radial flanges extending beyond the upper and lower ends of said roller; said flanges being positioned between the ends of the roller and the support plates and engageable with said support plates to maintain the roller in spaced relationship to the support plates and hinder the entrance of undesirable matter into contact with the bearings and shaft.

4. A blade according to claim 1 wherein said blade is used to remove snow from streets and roads and the guide is mounted on one side of the blade with the roller facing in the same direction as the blade such that snow may enter between the roller and the legs of the frame; including at least one hole in said first and second legs in the proximity of the juncture of said legs along said vertically extending edge, whereby snow entering between the legs and roller can exit from the frame through the last-mentioned hole.
